(57) **CLAIM**

The ornamental design for a carrying tray, as shown and described.

DESCRIPTION

FIG. 1 is a perspective view of a carrying tray embodying the ornamental design of the present invention;

FIG. 2 is a side view of the carrying tray;

FIG. 3 is an opposite side view of the carrying tray;

FIG. 4 is a front view of the carrying tray;

FIG. 5 is a rear view of the carrying tray;

FIG. 6 is a top view of the carrying tray; and,

FIG. 7 is a bottom view of the carrying tray.

The broken lines in FIGS. 1-7 are for illustrative purposes only and form no part of the claimed design.
